UNITED STATES PATENT OFFICE.

GEORGE LAWSON AND RICHARD C. LENT, JR., OF BROOKLYN, NEW YORK.

TWO-CYCLE INTERNAL-COMBUSTION ENGINE.

Application filed May 11, 1923. Serial No. 638,298.

To all whom it may concern:

Be it known that we, GEORGE LAWSON and RICHARD C. LENT, Jr., are citizens of the United States, residing at Brooklyn, in the county of Kings and State of New York, have invented new and useful Improvements in Two-Cycle Internal-Combustion Engines, of which the following is a specification.

This invention relates to engines and more particularly to internal combustion engines of the two cycle type.

One of the objects of the invention is the construction of an engine wherein the gas is compressed and heated within the same before its entrance into the combustion chamber, thereby increasing the power and eliminating the use of other outside cylinders now employed for this purpose.

Another object of the invention is the provision of an engine wherein the use of valves and cam shafts are dispensed with, thereby eliminating the grinding of valve seat and the replacement of cam shafts.

Another object of the invention is the provision of an internal combustion engine so constructed as to prevent leakage of the gas from the cylinders upon the compression stroke of the piston thus rendering it unnecessary to constantly keep tightening the crank shaft bearings and also permitting the crank case to be open whereby access may be had to the crank shaft, piston and connecting rod for the purpose of removing the same.

Another object of the invention is the provision of an engine having a double piston, operable in a pair of cylinders, one of the cylinders having a removable head so that the pistons may be withdrawn for cleaning the same.

A still further object is to provide a two cycle engine in which base explosions, which often occur in this type of engine, are eliminated.

A still further object is to construct an internal combustion engine which is exceedingly simple in construction and operation, cheap of manufacture, and highly efficient for the purpose intended.

With these and other objects in view the invention resides in the certain novel construction, combination and arrangement of parts, the essential features of which are hereinafter fully described in the specification, are particularly pointed out in the

claims and are illustrated in the accompanying drawing, in which:

Figure 1 is a vertical sectional view through our improved engine.

Figure 2 is a horizontal sectional view therethrough, on the line 2—2 of Figure 1.

Like characters of reference refer to like parts throughout the several views of the drawing.

Referring more particularly to the drawing, the reference numeral 10 designates what we shall term an outer cylinder, and 11 an inner cylinder. The inner cylinder 11 is arranged within the outer cylinder 10 and is spaced therefrom so as to define a compression chamber 12. This cylinder is concentric with the vertical axis of the cylinder 10, and the same is open at both ends, the top end terminating midway between the length of the outer cylinder, and the lower end extending below the outer cylinder and provided with an annular flange 13. The flange 13 receives the ends of a plurality of stanchions 14 rising from the base 15 and adapted to support the cylinders. The outer cylinder 10 is open at its lower end and is provided with an annular flange 16 for connection with the flange 13 of the cylinder 11 by means of bolts or the like. The upper end of the outer cylinder 10 is formed with an annular water jacket 17 whereby the cylinder may be cooled by either water or air, and closing the top of the cylinder 10 is a head 18. This head is also water jacketed and is secured to the cylinder by means of bolts 19, whereby the same may be readily removed for a purpose to be presently described.

Slidable within the cylinders 10 and 11 are pistons 20 and 21 respectively, the said pistons being fastened together at their tops by means of bolts 22, whereby the two move as a single unit. The piston 20 is, of course, larger in diameter than the piston 21, but the piston 21 is longer than the piston 20, and terminates at the lower end of the cylinder 11 when the piston is at its lowermost point of travel. The piston 20 is provided near its top with piston rings 23, and the piston 21 is likewise provided with piston rings 24, but arranged at the lower end of the piston. By the arrangement of the piston rings at opposite ends of the pistons it will be seen that any possibility of the escape of gas upon the compression stroke

of the pistons will be reduced to a minimum. The cylinder 10 is formed with an inlet port 25 opening into a combustion chamber 26 and having communication with the compression chamber 12. The numeral 27 designates an exhaust port which communicates with the chamber 26 and with the atmosphere, the same being disposed diametrically opposite the inlet port 25. Formed in the cylinder 11 and communicating with the chamber 12 is an inlet passage 28, having arranged therein a check valve 29 which permits gas to be sucked into the chamber 12 from the carburetor (not shown), or other source of supply, upon the upward stroke of the pistons, and preventing the escape of gas from the chamber 12 upon the downward stroke of the pistons. A connecting rod 30 has one end secured to the inner piston 21 by means of a wrist pin 31, and the other end of the connecting rod is secured to a crank 32, of the crank shaft mounted for rotation in bearings 33 carried by the base 15, one end of said crank shaft having secured thereto a fly wheel 34. The base 15 supports an oil-font 35 for the accommodation of oil employed for oiling the connection of the rod 30 with the crank 32.

In operation, and upon the upward stroke of the pistons (it being understood that a charge of gas has entered the combustion chamber), the intake and exhaust ports 25 and 27 will be closed by the outer piston 20, and the gas within the chamber 26 compressed. When the pistons have reached their extreme upward movement, the ignition takes place by reason of the timing of the spark produced by the spark plug 36 arranged in the head 18. This explosion causes the downward movement of the pistons thereby compressing the gas in the chamber 12 which has previously been drawn in through the valve 29 and inlet passage 28 during the upward stroke. When the pistons are at their lowermost position the ports 25 and 27 are uncovered so as to permit the escape of the scavenger gases through the port 27, and at the same time allows the compressed gases within the chamber 12 to rush into the chamber 26 through the port 25. The piston 20 is provided at its top with a baffle 37 which is arranged adjacent the inlet port 25 when the piston is in its lowermost position, the same serving to deflect the inrushing gases in an upward direction so as to assist in forcing out the scavenger gases. The cycle of operation is repeated so long as the engine is running.

It will be noted that by constructing an engine in the manner described, the head 18 may be removed from the cylinder 10 and the piston 20 disconnected from the

inner piston 21 by the removal of the bolts 22 after which the said piston 20 is withdrawn from the top of the cylinder 10. 65 Should it be necessary to remove both the pistons, the connecting rod 30 is disconnected from either the inner cylinder or the crank shaft, and both pistons removed simultaneously. This is very advantageous 70 when it is desired to replace piston rings or remove carbon from the pistons or cylinders. It also simplifies the manner of removing these parts and by reason of the arrangement of the double piston, all possibility of 75 the escape of gases is practically eliminated which also overcomes the necessity of keeping the crank shaft bearings in a tight condition as is the case in most two cycle engines, in order to prevent leakage through 80 the case. Furthermore it is to be noted that the gases in the chamber 12 are compressed and heated by reason of its location near the combustion chamber, before their entrance 85 into the combustion chamber, thereby increasing the power and fuel economy. Also the engine is free from any valves which may require grinding and cam shafts which are employed for operating the valves.

If desired the cylinder head 18 may be 90 removed and a vaporizer head substituted therefor in order to permit the engine to be run on kerosene.

While there has been shown and described what we deem the best embodiment of our invention it is to be understood that we do not desire to limit ourselves to the precise structural details herein described, but that changes, alterations and modifications as come within the claims may be resorted to 100 when desired.

What is claimed as new is:

In an explosive engine, an open base, and an inner cylinder open at both ends and provided with an annular flange at its lower end, a plurality of stanchions rising from said base and connected with said flange for supporting the same, an outer cylinder provided with a flange at its lower end and bolted to the flange of said inner cylinder, 110 a pair of spaced pistons movable simultaneously within said inner and outer cylinders in the same direction, the space between said cylinders constituting a compression chamber, means for removably securing said pistons together, and a removable head secured to the top of said outer cylinder whereby the removal of said head will permit withdrawal of said pistons through the top of said outer cylinder. 120

In testimony whereof we have affixed our signatures.

GEORGE LAWSON.
RICHARD C. LENT, JR.
